United States Patent Office

Des. 191,138
Patented Aug. 15, 1961

191,138

GARBAGE DISPOSER

Eugene E. Wieczorek, Racine, Wis., assignor to In-Sink-Erator Manufacturing Co., Racine, Wis., a corporation of Wisconsin

Filed June 13, 1960, Ser. No. 60,935

Term of patent 14 years

(Cl. D55—1)

FIG. 1

FIG. 2

FIG. 3

FIG. 4

FIG. 1 is a front elevational view of a garbage disposer embodying my new design;

FIG. 2 is a side elevational view, the side not shown being a mirror image of the side shown;

FIG. 3 is a rear elevational view of the garbage disposer;

FIG. 4 is a top plan view thereof.

The dominant features of my design reside in the portions shown in full lines.

I claim:

The ornamental design for a garbage disposer, substantially as shown and described.
